Patented May 9, 1922.

FIG. 1

FIG. 2

FIG. 3

INVENTOR

H. H. Berry:

H. H. Berry

ATTY.

UNITED STATES PATENT OFFICE.

HERBERT HENRY BERRY, OF LONDON, ENGLAND.

ELECTRIC RADIATOR.

1,415,770.

Specification of Letters Patent. Patented May 9, 1922.

Application filed May 3, 1921. Serial No. 466,519.

To all whom it may concern:

Be it known that I, HERBERT HENRY BERRY, a citizen of the United Kingdom of Great Britain and Ireland, and a resident of 86 Newman Street, London, W. 1, England, have invented certain new and useful Improvements in Electric Radiators, (for which I filed application in Great Britain, No. 3156, Feb. 2, 1920,) of which the following is a specification, such as will enable others skilled in the art to which it appertains to make and use the same.

This invention relates to electric radiators of the kind comprising an imitation fire in which an electric lamp or more than one is placed behind imitation fuel and may have a flicker-producing device such as a fan propelled by heat from the lamp or lamps and with which a resistance is employed to produce heat.

According to the invention the said resistance is placed above the imitation fire so as to radiate heat at a higher level than the fire said resistance and fire being mounted upon the same portable frame so that the appliance as a whole can be moved from one apartment to another. Means may be provided to support a kettle or cooking vessel and for the purpose of better heating the same the resistance may be movably mounted on the frame and be positioned in a semi-spherical, parabolic or other reflector which is movable with the resistance. The lamp or lamps above mentioned may be accessible in any way as by leaving the back of the fire open or providing a door through the imitation fuel.

An example of my invention is shown in the accompanying drawings in which:—

Fig. 1 is a front elevation.

Fig. 2 shows a side elevation with the reflector turned on its pivots and a kettle supported by the frame, and

Fig. 3 is an elevation of the back of the device.

The frame 1 carries the imitation fuel 2 under which an electric lamp 3 is arranged and has over it a fan 4 rotated by heat from the lamp 3 to produce the said flicker-effect.

The heating element or resistance 5 is mounted in a reflector 6 pivoted on the

frame at 7 and 8. A hook 9 is provided to support a kettle 10 or other utensil which could however be supported in other manner such as by resting on the frame 11 in front of the reflector 6.

I have not shown the electrical connections as these may be of various forms but in a general way will be plug and socket devices with suitable control switches.

With the apparatus as seen in Figs. 1 and 3 a realistic fire effect is obtained from the lamp 3 shining through the fuel and effective heating results from the resistance 5, the rays of heat from which are thrown forwardly by the reflector upon any person in front of the fire and thus a very realistic effect is obtained.

What I claim as my invention is:—

1. An electric radiator for imitating fire, comprising a frame, imitation fuel carried in the lower end of the frame, a lamp for illuminating said fuel, a reflector pivoted in the frame above the fuel, a heating element secured to and in front of said reflector, and means for supporting a utensil from the top of the frame over the reflector, whereby in one position of the reflector the heat of the heating element will be directed laterally from the same and in another position will direct the heat toward the bottom of a utensil supported on said means, while the fuel is illuminated imitating fire.

2. An electric radiator for imitating fire, comprising a frame, imitation fuel carried in the lower end of the frame, a lamp for illuminating said fuel, a reflector pivotally mounted in the frame above the fuel, and a heating element mounted on and in front of the reflector, whereby the reflector may be turned on its pivot to cause the heat of the heating element to be projected laterally therefrom and may be turned to another position for projecting the heat upwardly against the bottom of a utensil seated on the heating element.

In witness whereof I have hereunto set my hand in presence of two witnesses.

HERBERT HENRY BERRY.

Witnesses:

NANCY BERRY,
HENRY FAIRBROTHER.
